UNITED STATES PATENT OFFICE.

CLARENCE A. HILL, OF CANTON, OHIO.

DESIGN FOR A BLADE OR KNIFE FOR VEGETABLE-CUTTERS.

SPECIFICATION forming part of Design No. 30,366, dated March 21, 1899.

Application filed February 6, 1899. Serial No. 704,746. Term of patent 14 years.

To all whom it may concern:

Be it known that I, CLARENCE A. HILL, a citizen of the United States, residing at Canton, in the county of Stark and State of Ohio, have invented a certain new and useful and original Design for a Blade or Knife for Vegetable-Cutters, of which the following is a specification, reference being had to the accompanying drawings, forming part thereof.

10 In the accompanying drawings, Figure 1 is a top view. Fig. 2 is a bottom or under side view. Fig. 3 is a longitudinal section through line $x-x$, Fig. 2. Fig. 4 is a front edge view. Fig. 5 is a transverse section through line $y-y$, Fig. 2.

15 As shown in the drawings, the leading or material feature of my design consists in a blade or knife for vegetable-cutters.

The corrugations a extend from the cutting edge of the blade or knife A rearward and into the body, substantially as shown. The corrugations taper from the cutting edge of the blade or knife A to the points b , and between the tapered corrugations a are located 25 the tapered portions c , which tapered portions

c terminate between the corrugations a upon opposite sides of the plate A.

The blade or knife A consists of a rectangular body which is provided with plain faces upon its bottom and upper sides, except those 30 portions of the blade or knife provided with the tapered corrugations.

It will be understood that the tapered corrugations alternate upon opposite sides of the blade or knife proper.

At the ends of the blade or knife and adjacent to the corrugations are located the flat and plain portions d .

Having thus described my invention, what I claim as new, and desire to secure by Letters 40 Patent, is—

The design for a blade or knife for vegetable-cutters, substantially as shown and described.

In testimony that I claim the above I have hereunto subscribed my name in the presence 45 of two witnesses.

CLARENCE A. HILL.
